UNITED STATES PATENT OFFICE.

LEE C. SHARP, OF PLATTSMOUTH, NEBRASKA, ASSIGNOR TO ALFA-MAISE MANUFACTURING COMPANY, OF WILMINGTON, DELAWARE, A CORPORATION OF DELAWARE.

FORAGE-CUTTER.

1,390,548.

Specification of Letters Patent. Patented Sept. 13, 1921.

Application filed December 26, 1918. Serial No. 268,510.

To all whom it may concern:

Be it known that I, LEE C. SHARP, a citizen of the United States, and a resident of Plattsouth, in the county of Cass and State of Nebraska, have invented certain new and useful Improvements in Forage-Cutters, of which the following is a specification.

My invention relates to machines particularly adapted for cutting forage materials, as in preparing stock foods from coarse vegetation. Broadly, it is the object of my invention to provide a machine for cutting materials of the class mentioned into a meal-like product wherein there are no elongated shreds, straws, stalks, fibers or the like, and wherein all of the particles are of substantially uniform size. Particular objects of my invention are to provide in a machine of the class indicated, a feed-table which may be adjusted to various inclinations without changing the drive mechanism therefor; and to provide a casing or inclosure which may be readily opened to expose the cutting mechanism, without disconnecting any of the drive mechanism therefor.

In the accompanying drawings Figure 1 is a side view of a machine embodying my invention, Fig. 2 is a detail side view of the casing, showing the hood partially raised, Fig. 3 is a longitudinal vertical section, Fig. 4 is a detail horizontal section of the cutting cylinder, Fig. 5 is a rear elevation of the machine, and Fig. 6 is a detail section of the feed-table on the line 6—6 of Fig. 1.

In carrying out my invention according to the illustrated embodiment thereof, I provide a hollow base or pedestal 7 which is substantially rectangular in horizontal section, but with rounded corners, and having the lower end slightly flared and provided with a foot-flange, as shown. At the rearward side of the pedestal, intermediate the upper and lower ends thereof, is a flanged discharge opening 8, at the bottom of which is secured the lower edge of a curved guide-plate 9, said plate extending upwardly across the inside of the pedestal and being secured to the front side thereof as shown. Above the discharge opening there is a sight-opening, which is normally closed by a plate or sheet 10 of transparent material. The cutting cylinder is arranged in the open upper end of the pedestal, the cylinder-shaft 11 being journaled in suit-

able bearings formed at the upper edges thereof. The cylinder is formed of a series of plates or disks 12 which are notched peripherally to form teeth of which the forwardly moving faces are substantially radial and the rearward faces inclined, as shown. Said cutter-plates are fixedly secured to the shaft in an abutting or contacting series, the teeth of adjacent plates being staggered or offset relatively to each other. At one end the shaft 11 carries a pulley 13 which may be connected by a belt 14 with a suitable source of power. At the opposite end said shaft carries a pair of set-collars 15, between which is a loose collar 16, the latter carrying a pair of pins 17 which form a pivotal connection with the forked upper end of a rocking-lever 18. Said lever is pivoted on a bracket 19 secured on the side of the pedestal, and the lower end of the lever carries a roller 20 which fits in the undulatory groove of a barrel-cam 21, by rotation of which the cylinder-shaft 11 is oscillated longitudinally. Said cam 21 is carried on the protruding end of a drive-shaft 22 which extends horizontally through the lower portion of the pedestal, being journaled in bearings formed integrally therewith. The opposite end of said shaft carries a pulley 23 adapted to be driven by a belt from a suitable countershaft.

On the upper portion of the pedestal, at the rear side thereof, there is a pair of brackets 24 in which is journaled a shaft 25. A sprocket-wheel 26 on said shaft is connected with and driven by a sprocket-wheel 27 on the shaft 22, through the medium of a chain 28. To said shaft 25 the hood 29 is pivotally connected, said hood extending over the upper end of the pedestal so as to inclose the upper side and parts of the ends of the cutting cylinder, and continuing forwardly so as to similarly inclose the feed-cylinder 30. Said cylinder 30 is carried by a shaft 31 of which the ends are journaled in bearings carried at the ends of rods 32, the rearward ends of said rods being connected pivotally with the shaft 25. The shaft 31 passes through arcuate slots in the sides of the hood, which permit a rising and falling movement of the feed-cylinder relatively to the hood. The feed-cylinder is driven by a chain 33 connecting sprocket-wheels 34 and 35, mounted respectively on the shafts 25 and 31, as shown in Fig. 1.

At the upper end of the pedestal, on the front side thereof, a ledge or shelf 36 is formed integrally therewith, said shelf being recessed adjoining the rear edge thereof, to receive the removable ledger-blade 37 with which the teeth of the cutting cylinder co-operate. The front side-portions of the hood 29 hook over the front edge of the shelf 36, as will appear from Fig. 2. At the ends 10 of the shelf 36, there are pairs of depending lugs 38 in which are formed bearings for a pair of shafts 39 and 40. The rear shaft 39 is driven by means of a chain 41 connecting sprocket-wheels 42 and 43 disposed respectively on the drive-shaft 22 and said shaft 39. A pair of gears 44 are mounted on the ends of the shafts 39 and 40, and mesh operatively so that the latter shaft is driven thereby. To the shaft 40 there is pivotally connected a feed-table comprising laterally spaced bottom members 45 connected to each other by transverse bars or slats 46, and side portions 47 which extend in vertical planes. The pivotal connection of the feed-table with 25 the shaft 40 is made by means of bearing members 48 secured to the bottom members 45 of the table, and at the opposite or front end of the table there are similar bearing members 49 in which a shaft 50 is journaled. On the shafts 40 and 50 are mounted pairs 30 of sprocket-wheels 51 and 52 which are connected by chains 53, the sprocket-wheels being so proportioned and arranged that the upper parts of the chains pass through the slots between the bottom members 45 of the table. At suitable intervals the chains are provided with prongs or fingers 54 which are inclined rearwardly with reference to the direction of movement of the chains. The 35 feed-table is supported by pairs of adjustably connected bars 55 and 56, the ends of the upper bars 55 being pivotally connected with the intermediate cross-bar of the table, said upper bars being longitudinally slotted 40 as shown in Fig. 3, bolts 57 passing through said slots and the upper ends of the lower bars 56, and the lower ends of the latter being pivotally connected with lugs 58 at the foot of the pedestal 7. By various adjustments of said brace-bars 55 and 56, the table 45 may be supported at any desired inclination, from that shown in Figs. 1 and 3, up to a horizontal position, or even to a position at which the inclination is downward from the front to the rear end.

Material placed upon the feed-table is carried rearwardly by the feed-chains 53 and the fingers 54 thereon, and upon approaching the feed-cylinder 30 the material is 50 pressed downward and directed beneath said cylinder by means of curved resilient or yieldable guide-rods 59, of which the upper ends are secured to a cross-bar 60 carried at the upper front portion of the hood 29. Upon passing beneath the feed-cylinder the

material is compressed thereby into a relatively compact mat, of which the thickness may vary according to the volume of material being fed in a given time, the feed-cylinder rising or falling according to the thickness of the mat. By rotation of the feed-cylinder the mat is fed back over the shelf 36 and ledger-blade 37, so as to be engaged by the teeth of the cutting cylinder. On the sides of the hood 29, adjoining the cutting cylinder and arranged concentrically therewith, are curved guard-plates 61 which prevent any of the material being fed into the spaces at the ends of the cylinder between the end cutter-plates 12 and the sides of the hood. Owing to the use of separate driving means for the cutting cylinder, the latter may be conveniently driven at a high speed relatively to the speed of the feed mechanism, so that as each tooth of the cylinder passes the ledger-blade it will engage and shear off a very short piece of the mat of material protruding over the ledger-blade. The oscillating end-movement of the cylinder, caused by the rocking-lever 18, and being derived from the primary drive-shaft 22 of the feed mechanism, is at a rate definitely proportioned to the rate at which the material is fed. The cutting cylinder is preferably inclosed, except adjacent to the ledger-blade 37 and the feed-cylinder, by a screen 62. Said screen is disposed concentrically with the cylinder and is preferably divided into two parts which are separable in the horizontal plane of the upper end of the pedestal, the upper portion of the screen being attached to the hood, and the lower portion being attached to the pedestal. Thus, upon raising the hood, as indicated in Fig. 2, the cutting cylinder is fully exposed and may be readily removed, as for sharpening or renewing the cutter-plates 12.

The operation of the machine will be apparent from the foregoing. The material, being fed to the cutting cylinder at a suitable rate, is engaged by the multiplicity of teeth on said cylinder and immediately reduced to small particles of a meal-like consistency, there being no spaces in the cylinder between the plates 12 into which the material may pass so as not to be cut as soon as it extends beyond the ledger-blade. The prompt disintegration of the material is further facilitated by the longitudinal oscillation of the cutting cylinder. In the event that any portion of the material, by lying exactly parallel with the edge of the ledger-blade, should be able to pass into the cylinder-space without being cut into small particles, such material will be merely carried around the cylinder, within the screen 62, until, by again striking the ledger-blade and being sheared by the teeth, it is reduced to particles small enough to pass through the inclosing screen. The feed-table may be

readily adjusted to any desired angle or inclination, as found most convenient for facilitating the loading of the material thereon, and such adjustment of the feed-table 5 does not interfere with the driving mechanism therefor. The feed-cylinder may automatically raise and drop according to the amount of material passing thereunder, and the opening of the hood, to expose the cutting cylinder and provide access to the interior of the machine, may also be effected without changing or interfering in any way with the drive mechanism for the several parts.

10 15 Now, having described my invention, what I claim and desire to secure by Letters Patent is:

1. In a forage cutter, a cutting cylinder, a fixed support having bearings for said cylinder and inclosing the lower portion thereof, a drive-shaft mounted on said support, a feed-cylinder, actuating means therefor connecting the same with the drive-shaft, and a casing-member covering the upper 20 25 portion of the cutting-cylinder and feed-cylinder, said casing-member, the feed-cyl-

inder and the actuating means therefor being swingable about the axis of the drive-shaft to fully uncover and expose the cutting-cylinder.

2. In a forage cutter, cutting mechanism, a stationary support adjacent thereto, a drive-shaft journaled on said support, a slotted feed-table pivoted at one end on said drive-shaft, a shaft journaled on the opposite end of said table and parallel with said drive-shaft, aligned pairs of sprocket-wheels mounted on said shafts, endless feed-chains connecting each pair of the sprockets and movable through the slots of the table, and 30 35 40 adjustable supporting means for holding the table at the various inclinations relative to said support to which it may be moved by swinging about said drive-shaft.

3. A structure as set forth in claim 1, including a two-part screen disposed around the cutting-cylinder, one part of said screen being carried upon the fixed support, and the other part being carried upon the swingable casing-member.

45 LEE C. SHARP.
